CLAIM

The ornamental design for a combined peanut dolls and case, as shown and described.

DESCRIPTION

FIG. 1 is a front elevation of a combined peanut dolls and case showing my new design;

FIG. 2 is a front elevation of the combined peanut dolls and case shown with the case in the open position;

FIG. 3 is a back view of the combined peanut dolls and case shown in the open position, showing the hinges;

FIG. 4 is a side view of the combined peanut dolls and case shown in the open position, to show the profile of the dolls in the case;

FIG. 5 is an end view of the combined peanut dolls and case showing the strap attachment to the case;

FIG. 6 is a top view of the combined peanut dolls and case in the closed position; and,

FIG. 7 is a bottom view of the combined peanut dolls and case.

The strap is shown fragmented in FIGS. 4 and 5 for ease of illustration.
